METHOD OF AND APPARATUS FOR CONTROLLING FLUID FUEL BURNERS FOR BOILERS

Guido Wünsch and Kurt Blasig, Berlin-Steglitz, Germany, assignors to Askania-Werke A. G., a company of Germany

Application January 30, 1935, Serial No. 4,204
In Germany January 30, 1933

13 Claims. (Cl. 236—26)

This invention relates to a novel method and apparatus for controlling fluid fuel burners such as oil burners used in marine boiler installations and the like, although it is to be understood that 5 the invention is applicable to other types of installations. Among other objects, the invention aims to provide novel means for controlling a series of burners in accordance with the boiler load and also controlling the individual burners 10 of the series. The idea is to obtain satisfactory graduated control of the burners and to avoid the necessity of employing a larger number of burners to accomplish the same result. Furthermore, the invention aims to provide a novel 15 method whereby the individual burners of the series start in succession and the supply of fuel and air to the individual burners is increased according to the boiler load. The invention also contemplates the provision of novel means for 20 controlling both the primary air and secondary air for burners of the atomizer type in accordance with the quantity of oil or other fluid fuel admitted to the burners.

Other aims and advantages of the invention 25 will appear in the specification, when considered in connection with the accompanying drawings, wherein:

Figs. 1 and 1A disclose more or less diagrammatically an illustrative example of apparatus 30 used for practicing the invention.

Referring particularly to the drawings, it will be assumed for the purposes of illustration that the boiler is of the marine type in which a plurality of atomizing burners 10, 10', etc. are employed. The burners are shown for convenience as being arranged on opposite sides of the boiler furnace. In this example, fuel oil is supplied to the burners through oil conduits 11 connected to an oil header 12 representing a source of oil 40 and having a series of oil control valves 13, 13' of the needle type. In this instance, three such oil lines are shown, merely to indicate that any number of burners may be employed and controlled automatically in accordance with the invention.

The oil is atomized in the burners 10 and 10' by means of the ordinary centrifugal turbines (not shown), or by any other well known means employed in the art. Primary air to support 50 combustion is supplied by means of ordinary blowers 14, 14' through conduits 15 and 15' respectively which terminate in nozzles around the ends of the oil conduits. The supply of primary air is varied by means of conduits 16, 16' which 55 open into the atmosphere and are controlled by

butterfly valves 17 and 17', said valves being preferably controlled automatically by apparatus later to be described. When the butterflies are closed, the maximum amount of primary air will be admitted to the burners; while the air will be vented to the outside when the butterflies are in their open position. The butterflies are here shown as being controlled hydraulically and automatically, although it is to be understood that they may be automatically controlled by any other suitable means. Herein, the valves are connected to pistons 18, 18' by means of arms and links 19, 19', 20, 20' respectively. The pistons are arranged in cylinders 21, 21' and are shown as being normally urged toward the valve 15 opening positions by means of springs 22, 22'. The hydraulic mechanism for operating these pistons will be described later.

In the present instance, secondary air is also supplied automatically to the burners by means 20 of a separate blower 23 having a main outlet 24 leading to the branch conduits 25, 25' and, thence, to the respective burners. The supply of air to the branch conduits is shown as being controlled by a main damper 26 actuated by a 25 piston 27 in a cylinder 28. The supply of secondary air to the individual burners is also automatically controlled in a manner later to be described by dampers 29, 29' in the branch conduits these dampers being actuated by pistons 30 30, 30' in cylinders 31, 31'. While the volume of air delivered by the blower 23 to the branch conduits may be controlled by varying the speed of the blower, it is here shown as being controlled by the butterfly 26 to set up a predetermined 35 pressure difference between the main secondary air conduit and the combustion chamber of the boiler in response to the total boiler load. The manner in which the damper 26 in the outlet-conduit 24 is automatically governed in response 40 to the load on the boiler, will be later explained.

Referring to Fig. 1A, it will be understood that oil under constant pressure is delivered to the header 12. The needle valves 13, 13' and 13'' are normally held closed by means of compression 45 springs 34, 34', 34'' and they are adapted to be operated in succession or in series by bell-shaped cams 35, 35' and 35'', the arrangement being such that the valve 13 opens first. These cams are shown as being carried on a single piston rod 50 36 operated by a piston 37 arranged in the cylinder 38. The valves are controlled automatically in accordance with the boiler load by means of a jet pipe regulator or governor of the "Askania" type, reference being made to Reissue 55

Patent No. 19,114 and Patent No. 1,721,800. In this case, the steam pressure in the steam header governs the action of the regulator by a steam conduit 39, the pressure being a measure of the boiler load. The pressure acts on a bellows type diaphragm 40 which, in turn, exercises a controlling effect through a spring-urged pivoted arm 41 acting upon a rod or bar 42 on the jet pipe 43, which is supplied with oil or liquid under constant pressure from a suitable source, not shown, delivered by a conduit 44. The jet pipe delivers oil to one or the other of conduits 45 and 46 leading to opposite ends of the cylinder 38, the arrangement being such that as the steam pressure increases in the header the jet delivers oil to pipe 45 and moves the piston to the left, thereby cutting down the oil supply to the burners.

In this instance, the regulator has a governing slider 47 above the jet pipe 43 acting on a counterbalanced arm 48 and normally urging a push rod 49 against a compression spring 50, which acts on a push rod 51 carrying a roller 52 contacting with a cam 53 on the piston rod 36. The arrangement is such that when the piston is moved in either direction, the mechanism counterbalances the jet pipe and brings it to rest after the piston 37 has moved the cam 53 into a position representing the pressure in the steam header. It will be understood that when the burners are first started, there will be no pressure in the steam header; consequently the jet pipe will deliver oil to the conduit 46 and move the piston 37 to the right to open the oil valves in succession. When the pressure rises to a predetermined amount, further movement of the piston is arrested by the governing apparatus through the cam 53.

As hereinbefore stated, the primary and secondary air are also controlled automatically. In this instance, the control is effected by hydraulic relay mechanism; although it is to be understood that it may be operated electrically or otherwise. Herein, oil under constant pressure is delivered to a header 54 having a series of main outlet valves 55, 55' and 55'' opposite the fuel oil valves and leading to casings 56, 56', 56'' and these valves are normally held closed by compression springs 57, 57' and 57'' on their stems which are actuated by the cams 35, 35', 35''. The valve stems carry second valves 58, 58', 58'' controlling return ports 59, 59', 59'' leading to a common return conduit 60. The arrangement is such that when one of the outlet valves 55 is fully opened, the corresponding return valve is closed. From the casings 56, 56' conduits 61, 61' lead directly to the inner ends of cylinders 21, 21'. As the oil pressure in these conduits increases in response to the opening of the fuel oil valves 13, 13', the pistons 18, 18' are moved outwardly against the springs 22, 22', thereby closing the butterflies 17, 17' in proportion to the quantity of fuel oil supplied. Simultaneously, the oil pressure is admitted to the upper ends of four-way valve casings 62, 62', 62'', having controlling pistons 63, 63', 63'' on the upper ends of piston rods 64, 64', 64'', the piston rods being normally urged upwardly by adjustable compression springs 65, 65', 65'' at their lower ends. The springs are so adjusted that a predetermined oil pressure, measured by the pressure gauges at the upper ends of the valve casings, is required to actuate the relay valves. The arrangement is such that when a predetermined minimum quantity of fuel oil is supplied the relays will operate

immediately to fully open the dampers in the secondary air branch conduits and thereby admit a supply of secondary air.

Referring to the first four-way valve, for example, the oil pressure in line 61 has forced the piston 63 downwardly. The piston rod carries pairs of spaced pistons 66 and 67 in the casing which control the ports of pairs of conduits 68, 69 and 70 and 71, respectively connected to the cylinder 31 and to the return line 72 leading to a tank 73 from which oil is supplied by a constant pressure pump to the casing of the four-way valve through supply line 74. In this instance, the same pump supplies oil under pressure to all of the four-way valve casings and the return lines lead to the tank. Of course, any source of oil under constant pressure may be employed. The supply conduit 74 leads into the casing between the pistons 66 and 67 so that oil may be delivered either to the conduit 68 or 70, depending upon the position of the valve. In the position shown, oil under pressure is being supplied to the conduit 70 so that it moves the piston 30 to the right and fully opens the damper 29 in the secondary air conduit 25. At the same time, oil is being exhausted or returned from the right hand end of the cylinder 31 through the conduit 68 and the return line 69. The second relay has fully opened the secondary air damper 29' after the oil valve 13' is only slightly opened. When the pistons are at the upper end of their stroke and no fuel oil is being supplied to a burner, the oil under pressure passes through the conduit 68 to move the piston 30 to the left and close the butterfly valve 29 (see the position of the parts in the casing 62'').

It is sometimes desirable also to control the quantity of secondary air in accordance with the boiler load. To this end a second main regulator controls the damper 28 in the discharge outlet 24 of the secondary blower or fan 23 to create a differential pressure between the boiler furnace and said main secondary air conduit in response to the load represented by the position of a cam 80 relatively to a push-rod 79. This regulator is similar to the regulator for controlling the fuel oil valves. It also includes a jet pipe 75 which receives oil under constant pressure from a conduit 76 and discharges into conduits 77 and 78 leading to the cylinder 28. The position of the jet pipe is controlled by a rod 79 acted upon by a cam 80 on the piston rod 36 and counterbalanced by the differential pressure acting on a diaphragm 81 in a diaphragm casing 82 which is connected by conduits 83 and 84 to the main secondary air conduit and the boiler furnace, respectively. The diaphragm is shown as having a rod 85 which acts on a pivoted, counterbalanced lever 86 and an adjustable slider 87 which engages the jet pipe. As the boiler load increases and the fuel oil valves are opened to a greater extent, the regulator acts to admit oil under pressure through the conduit 77 to operate the piston 27 and open the damper 26, thereby increasing the volume of secondary air. When the differential pressure between the boiler furnaces and the main secondary air conduit exceeds a predetermined amount, it will tend to move the jet pipe 75 in the opposite direction.

From the foregoing description it will be seen that the novel control method enabling a control of heat supply, variable within great limits, is characterized by a step-by-step control at low load values, namely by starting and shutting off 75

individual burners burning at their minimum capacity. At load values higher than could be carried by all burners burning at their lowest capacity the control becomes gradual, namely by increasing the fuel and air supply to all burners equally and simultaneously, thereby obviating an individual secondary air control for each burner, since all burners have a flame of equal size. Thus a maximum efficiency is obtained.

Having thus described the method and illustrative apparatus for practicing the invention, it will be understood that the invention is not limited to a strict conformity with the description thereof, but is capable of various embodiments and modifications, within the scope of the appended claims.

What is claimed is:

1. In a boiler installation having a plurality of fluid fuel burners; separate valves for controlling the supply of fuel to the burners; a regulator actuated by variations in the boiler load; a series of cams for operating said valves connected to be actuated by said regulator; a series of hydraulic relays for controlling the supply of air to said burners; and a series of controlling valves for said hydraulic relays also connected to be actuated by said cams.

2. In a steam boiler installation having a plurality of fluid fuel burners and blowers for supplying primary and secondary air thereto, separate valves for controlling the supply of fuel to the burners; a regulator connected to operate the valves in succession in response to the boiler load; adjustable means to control the initial supply of secondary air when each burner is started and to control the supply of primary air according to the quantity of fuel supplied to the burners; and a second regulator connected to control the volume of air delivered by the secondary air blower in response to the boiler load.

3. The combination with a steam boiler having a plurality of fluid fuel burners, of a source of fuel; a source of combustion air; means connected to be operated in response to the magnitude of the boiler load below a predetermined low load value, for successively rendering operative and maintaining at a minimum capacity the fluid burners, one after another, means for equally and simultaneously increasing the fuel supply to all burners when exceeding said low load value after rendering operative the last of said burners; and means connected to be operated in response to the boiler load for governing the combustion air supply to all operating burners.

4. The combination with a steam boiler having a plurality of fluid fuel burners, of a source of fuel; a source of combustion air; means connected to be operated in response to the magnitude of the boiler load below a predetermined low load value for successively admitting a minimum amount of fuel to the burners, one after the other, means for equally increasing the fuel supply to all burners when exceeding said low load value after admitting fuel to the last of said burners; and means connected to be operated in response to the boiler load for governing the combustion air supply to all operating burners.

5. The combination with a steam boiler having a plurality of fluid fuel burners, of a source of fuel; a source of combustion air; means connected to be operated in response to the magnitude of the boiler load below a predetermined low load value for successively admitting a minimum amount of fuel to the burners, one after the other, means for equally increasing the fuel sup-

ply to all burners when exceeding said low load value after admitting fuel to the last of said burners; means connected to be operated in response to the boiler load for governing the combustion air supply to the burners; and means for shutting off an air supply to dead burners.

6. The combination with a steam boiler having a plurality of fluid fuel burners, of a source of fuel; a source of combustion air; means connected to be operated in response to the magnitude of the boiler load below a predetermined low load value for successively admitting a minimum amount of fuel to the burners, one after the other, means for equally increasing the fuel supply to all burners when exceeding said low load value after admitting fuel to the last of said burners; means for admitting primary combustion air to the burners in response to the admitted amount of fuel; and means connected to be operated in response to the boiler load for governing the admission of secondary combustion air to all operating burners.

7. The combination with a steam boiler having a plurality of fluid fuel burners, of a source of fuel; a source of combustion air; means connected to be operated in response to the magnitude of the boiler load below a predetermined low load value for successively admitting a minimum amount of fuel to the burners, one after the other, means for equally increasing the fuel supply to all burners when exceeding said low load value after admitting fuel to the last of said burners; means for admitting primary combustion air to the burners in response to the admitted amount of fuel; means connected to be operated in response to the boiler load for governing the admission of secondary combustion air to all burners; and means for shutting off the supply of secondary air to dead burners.

8. In combination with a steam boiler having a plurality of fluid fuel burners, automatic control means responsive to changes in boiler load below a predetermined low load value and connected to successively admit a minimum amount of fuel to the burners, one after the other, means for equally increasing the supply of fuel to all burners when exceeding said low load value after admitting fuel to the last of said burners; automatic governing relays also connected to be operated by said control means; means controlled by said governing relays for supplying primary air to the respective burners whereby both the supply of primary air and fuel are controlled in proportion to the boiler load; means for supplying secondary air to the burners in response to the boiler load; and automatic means also connected to be operated by said governing relays and arranged to admit secondary air to operating burners and to shut off a supply of secondary air to dead burners.

9. In combination with a steam boiler having a plurality of fluid fuel burners, automatic control means including a master regulator responsive to variations in the boiler load below a predetermined low load value, and a plurality of master cams, one for each burner, operable by said regulator and connected successively to control the admission of a minimum amount of fuel to the burners, one after the other, means for equally and simultaneously increasing the fuel supply to all burners when exceeding said low load value after admitting fuel to the last of said burners; automatic governing relays also connected to be operated by said control means; means controlled by said governing relays for

- supplying primary air to the respective burners, whereby both the supply of primary air and fuel are controlled in proportion to the boiler load; means for supplying secondary air to the burners; and automatic means also connected to be operated by said governing relays and arranged to admit secondary air to operating burners and to shut off a supply of secondary air to dead burners.
10. Apparatus as set forth in claim 9 comprising in addition an additional regulator responsive to changes in boiler load and connected to control the total supply of secondary air.
11. In a steam boiler installation having a plurality of fluid fuel burners, impulse means connected to be operated in response to variations in the boiler load; means controlled by said impulse means to start and shut off said burners one after the other in response to boiler load impulses of a predetermined low load impulse range which corresponds to a low operating capacity of the burners individually and collectively; means also controlled by said impulse means connected to increase or decrease the fuel supply to all operating burners equally and simultaneously in response to higher load impulses corresponding to the collective high load capacity of the burners exceeding their collective low operating capacity; means for supplying primary air at all times to each burner in response to the amount of fuel burnt by the same; and means for supplying secondary air at all times to the operating burners in response to the boiler load.
12. In a steam boiler installation having a plurality of fluid fuel burners, impulse means connected to be operated in response to variations in the boiler load; means controlled by said impulse means to start and shut off said burners one after the other in response to boiler load impulses of a predetermined low load impulse range which corresponds to a low operating capacity of the burners individually and collectively; said impulse controlled means also being connected to increase or decrease the supply of fuel to all of the burners simultaneously after all burners have been started at their collective low operating capacity and in response to impulses of a higher load range corresponding to the capacity range of the collective burners exceeding their collective low operating capacity; and means connected to supply combustion air at all times to the operating burners in response to the boiler load impulses.

13. The combination with a steam boiler installation having a plurality of fluid fuel burners, of a source of fuel; means responsive to the boiler load connected to start the burners, one after another, and operating each of the burners at a minimum capacity until all burners have been started; means connected to increase the supply of fuel simultaneously to all of the burners as the boiler load further increases; and means also responsive to the boiler load to control the combustion air supply to all operating burners.
